UNITED STATES PATENT OFFICE

FRANK P. MILLER AND LEWIS SKEEL, OF MEADVILLE, PENNSYLVANIA, ASSIGNEES
TO McCROSKEY TOOL CORPORATION, OF MEADVILLE, PENNSYLVANIA, A CORPORATION OF PENNSYLVANIA

POWER HAMMER

Application filed March 14, 1927. Serial No. 175,242.

This invention relates to power operated hammers of the type in which a compressible power transmitting medium is employed between the driving and driven members.

5 Briefly stated an important object of this invention is to provide an air hammer in which the construction of parts is such that the cost of manufacture is substantially reduced as compared with other hammers of 10 which we know and in which novel means are provided to avoid loosening of various parts of the hammer as a result of vibration incident to use.

Another equally important aim is to provide 15 a hammer of the character specified having reliable means by which the shock to the operator of the hammer is reduced to a minimum.

Another purpose is to provide a hammer 20 in which the power transmitting medium such as air between the driving and driven members may be nicely regulated to permit the operator to control the response of the driven member to the reciprocation of the 25 driving member.

Other objects and advantages will be apparent during the course of the following description.

In the accompanying drawings forming a 30 part of this application and in which like numerals are employed to designate like parts throughout the same:

Figure 1 is a longitudinal sectional view through the hammer.

35 Figure 2 is a similar view taken at right angles to Figure 1.

Figure 3 is a transverse sectional view taken on line 3—3 of Figure 1.

40 Fig. 3^a is a sectional view through a modification.

Figure 4 is a longitudinal sectional view illustrating a slight modification of the invention.

45 Figure 5 is a detail sectional view illustrating another expression of the invention.

Figure 6 is an end view of the intermediate piston illustrated in Figure 5.

50 Figure 7 is a detail longitudinal sectional view through a further modification of the invention.

Figure 8 is an end view of the intermediate piston illustrated in Figure 7.

In the drawings the numerals 10 and 11 designate inner and outer closely interfitting tubular members which together form the 55 barrel of the hammer and which are connected at the rear portions thereof to the annular clamp 12 of a housing 14. Figure 3 clearly illustrates that the housing is provided with a pair of aligned apertured ears 60 15 receiving a bolt 16 having a nut 17 by which the clamp 12 may be secured in binding engagement with the barrel. Figure 1 illustrates that the bolt 16 extends through a transverse groove 18 in the outer tube 11 to 65 positively hold the barrel against turning and endwise shifting as a result of the vibration to which tools of this character are known to be subjected. The illustrated connection 70 between the barrel and the clamp 12 avoids the necessity of employing interfitting threads which are likely to loosen because of vibration. As suggested in Figure 3^a the transverse groove 180 may be made deep 75 enough to extend into the inner tubular member 10 to permit the bolt 16 to have binding engagement with both the tubes 10 and 11.

The outer tube 11 extends to a point well in advance of the inner tube 10 and is peened or flanged inwardly as indicated at 19 to limit 80 the forward movement of a tool holding nib 20. The nib 20 has a central longitudinally extending opening for the reception of the attaching portion 21 of a tool 22 and by reference to Figure 1 it will be seen that the 85 attaching portion 21 terminates at a point rearwardly of the nib so the same may receive the power blows of a driven piston 24.

In carrying out the invention the driven piston 24 and the driving piston 25 are 90 mounted to reciprocate within the inner tube 10 so that the air compressed on the forward stroke of the driving piston is utilized to advance the driven piston in much the same manner as many other pulsating hammers. 95 In more specifically alluding to this feature, however, it might be pointed out that the forward stroke of the driving piston compresses the air in the main compression chamber defined by the two pistons so that this 100

compressed air acts as a power transmitting medium by which the driven piston 24 is caused to strike the rear end of the tool shank 21. On the rear stroke of the driving piston 25 a vacuum is created between the two pistons so that the driven piston is retracted.

Figure 1 illustrates that the driving piston 25 is provided with a supplemental compression chamber 26 adapted to snugly receive a cylindrical extension 27 on the rear end of the driven member. The air within the chamber 26 is compressed on the forward stroke of the driving piston and the resulting pressure against the extension 27 adds to the force of the blow.

Figure 1 illustrates the various parts of the hammer in a neutral position so that reciprocation of the driving piston 25 will have no effect on the driven piston 24. However, should it be desired to operate the tool for its intended purpose the operator has only to bring the member 22 into pressure contact with the work such as a rivet or a rock so that the nib 20 will be retracted against the influence of a coil spring 28. By thus moving the tool forwardly into pressure contact with the work the piston 24 is moved rearwardly in the barrel to close or partly close the ports 29 depending, of course, on the degree of forward pressure exerted by the operator. In case only a very slight forward pressure is exerted by the operator on the tool the piston 24 will be moved partly over the ports 29 so that the reciprocation of the piston 25, will through the medium of the lightly compressed air, advance the piston 24 with only limited force into engagement with the shank 21.

In case the force of the blow is to be added to, the forward pressure exerted by the operator on the tool is increased so that the piston 24 will be caused more completely to close the ports 29. To secure the full force of the blow it is only necessary to exert sufficient forward pressure to cause the piston 24 to entirely close the ports 29.

Attention is especially invited to the fact that the ports 29 increase in area toward the rear ends thereof to provide for the sensitive control of the driving connection between the two pistons.

The intermediate portion of the nib 20 is annularly enlarged to define a pair of shoulders, the forward one of which cooperates with the inwardly peened terminal of the tube 11, while the rear shoulder of the annular enlargement is engaged by the forward portion of the spring 28. It will be seen that the spring 28 holds the nib 20 and the tool 22 in fully advanced position when the apparatus is not in active use whereby reciprocation of the driving piston will have no effect.

Also the spring assists the operator in controlling the extent to which the tool 22, the nib 20 and the piston 24 are moved backward

in partially or completely closing the ports 29. Furthermore, the spring 28 permits the nib 20 to move rearwardly in case the hammer is accidentally dropped. This avoids the possibility of damage to the nib and associated parts.

The shoulder 30 on the tool 22 transmits the rearward movement of the tool to the nib 20 and also limits the extent to which the rear terminal of the shank 21 projects beyond the rear end of the nib. Thus it is that the nib 20 is mounted for free movement in the forward portion of the tube 11 and may be moved rearwardly against the tension of the coil spring 28 only by the exertion of forward pressure on the tool by the operator to control the degree of response of the driven piston to the reciprocation of the driving piston as suggested in the opening paragraphs of this specification.

One of the most important features of the invention resides in the fact that the tube 10 is externally and longitudinally grooved as indicated at 32 to cooperate with the outer tube 11 in the formation of air conduits, the inner tube being provided with the ports 29 and ports 33 in communication with these grooves to permit of the easy flow of air under the influence of the several pistons.

In further alluding to the above feature it is pointed out that on the rear strokes of the driving and driven piston the air rearwardly of the driving piston may travel forwardly through the grooves 32 and enter the tube 10 through ports 33 in advance of the driven piston to avoid the formation of a vacuum in advance of the piston and in fact to aid in the rearward movement of the driven piston.

The driving piston has universal connection with a pitman rod 31, the rear portion of which receives the interfitting crank pins 34 of a pair of driving disks 35. The driving disks are counter-balanced to avoid unnecessary vibration.

The disks are provided with laterally projecting spindles 36 and 37 mounted on anti-friction elements 38, one of the anti-friction elements being carried by the fixed side of the housing 14 while the other one is carried by a detachable side plate 39. At this point it might be stated that the side plate 39 is threaded into place and is held by a set screw 40 against loosening as a result of vibration. Figure 1 clearly illustrates that the set screw has the forward portion thereof somewhat tapered for engagement with the chamfered edge of the opening into which the side plate 39 is threaded. The firm engagement of the set screw 40 with the chamfered edge of the opening will positively hold the side plate against turning.

The improved hammer is provided with a handle 42 having an attaching plate 43 designed to be held in place by the cap screws 44 or other suitable means. It is important

to note that the openings in the attaching plate 43 freely receive the shanks of the cap screw 44 to permit of a limited movement of the handle with respect to the remainder of the tool. Figure 2 illustrates that a pad of rubber, cork or other yieldable material is interposed between the attaching plate 43 and the adjacent portion of the housing 14 to reduce the shock on the operator to a minimum. In lieu of a pad as illustrated a bowed spring may be employed.

The spindle 37 is extended through and terminates beyond the fixed hub 46 of the side plate 39 and is longitudinally socketed to receive the attaching portion of a flexible or other driving unit. Driving pins 47 are extended across the longitudinal socket in the spindle 37 and have flats adapted to be engaged by the flattened surface of the driving member. By this construction the turning of the driving member such as a flexible shaft will result in the turning of the spindle 37 and in the reciprocation of the piston 25.

The fixed hub 46 is provided with radial lugs 81 by which the coupling of a flexible chain or the like may be detachably connected to the hammer.

Attention is invited to Figure 4 which illustrates that the driving piston 49 may be provided with a central extension 50 adapted to be snugly received in a supplemental compression chamber 51 in the rear end portion of the driven piston 52. It will be observed that the other parts of the hammer may be much the same as the hammer illustrated in Figures 1 and 2.

In the form of invention illustrated in Figures 5 and 6 both the driving and driven pistons 53 and 54 are provided with axial reduced extensions 55 and 56 adapted to be snugly received in supplemental compression chambers 58 in a free intermediate piston 59. Figure 6 illustrates that the free intermediate piston 59 is provided with longitudinal grooves 60 by which the pressure in the spaces at opposite ends of the free intermediate piston is equalized on the power stroke of the driving piston and by which the vacuum at both ends of the intermediate piston is equalized during the retraction of the driving piston.

Figures 7 and 8 illustrate still another mechanical expression of the invention as the driving and driven piston 61 and 62 respectively are provided with aligned supplemental chambers 63 and 64 respectively to snugly receive the reduced end portions of the free intermediate piston 65. The piston 65 is provided between the ends thereof with longitudinal grooves 66 by which the pressure as well as the vacuum is equalized during the operation of the hammer. The grooves 66 also allow of the passage of the air through the ports 29 when the driven pis-

ton 62 is positioned to neutralize the action of the rapidly reciprocating driving piston.

Having thus described the invention, what is claimed is:

1. A power hammer comprising a barrel having inner and outer tubular members, the outer tubular member being extended beyond the inner tubular member and having a retainer, a tool holding nib slidable within the extended portion of said outer tubular member and being provided with a shoulder cooperating with said retainer in limiting endwise movement of the nib, a spring confined between said shoulder and the forward terminal of the inner tubular member, said inner tubular member being provided with a port for the discharge of air, a piston within said barrel and adapted to control said port, and means carried solely by and movable with said piston with respect to said port. 70

2. A power hammer comprising a barrel, driving and driven pistons within said barrel, and a free intermediate piston between said driving and driven pistons, said free intermediate piston being provided with a passage for air, said passage communicating with the spaces at opposite ends of the intermediate piston. 80

3. A power hammer comprising a barrel having a main chamber, driving and driven pistons in said chamber, and an intermediate piston between said driving and driven pistons and having means establishing communication with the spaces at the opposite ends of the intermediate piston, said chamber being adapted for the reception of a compressible fluid by which power is transmitted from the driving to the driven piston. 95

In testimony whereof we affix our signatures.
